TOY ANIMAL FIGURE

Joseph Anello, Cahokia, Ill., assignor to Judy Deb Manufacturing Co., Inc., St. Louis, Mo., a corporation of Missouri

Filed Sept. 7, 1965, Ser. No. 86,871

Term of patent 3½ years

(Cl. D34—2)

FIG. 1

FIG. 2

FIG. 3

FIG. 4

FIG. 5

FIG. 1 is a top view of a toy animal figure embodying my new design, shown open and flattened.

FIG. 2 is a bottom view thereof.

FIG. 3 is a side view thereof.

FIG. 4 is a side view thereof shown coiled in an arc, so that the two ends are adjacent each other.

FIG. 5 is a top view, coiled as shown in FIG. 4.

I claim:

The ornamental design for a toy animal figure, substantially as shown.
